United States Patent

Des. 235,522
Patented June 24, 1975

235,522

COMBINED MEASURING AND CALCULATING SCALE

Elmer Harold Cunningham, P.O. Box 552,
Bowie, Tex. 76230

Filed Feb. 1, 1973, Ser. No. 329,203

Term of patent 14 years

Int. Cl. D10—04

U.S. Cl. D10—71

The figure is a perspective view of a combined measuring and calculating scale, the center section having been omitted for convenience of illustration, the opposite sides not shown are plain and unornamented.

I claim:

The ornamental design for combined measuring and calculating scale, as shown.
